UNITED STATES PATENT OFFICE.

SAMUEL M. SKIRVING AND AMBROSE J. B. BERGER, OF PHILADELPHIA,
PENNSYLVANIA.

STREET-SWEEPING MACHINE.

SPECIFICATION forming part of Letters Patent No. 444,025, dated January 6, 1891.

Application filed August 5, 1890. Serial No. 361,084. (No model.)

To all whom it may concern:

Be it known that we, SAMUEL M. SKIRVING and AMBROSE J. B. BERGER, citizens of the United States, both residing in the city and county of Philadelphia, State of Pennsylvania, have invented a new and useful Improvement in Street-Sweeping Machines, which improvement is fully set forth in the following specification and accompanying drawings.

10 Our invention relates to improvements in street-sweeping machines; and it consists, first, of mechanism, substantially as described, for raising and lowering the rotary brush of the device; second, of a novel brush-guard and dirt-gatherer, substantially as described; third, of a tension device for the sprocket-chains of the bucket-carrying apron; fourth, of a movable box for receiving the dirt from the conveyer and a track therefor, substantially as described; fifth, of a novel conveyer, substantially as described; sixth, of the combination of parts herein set forth.

Figure 1 represents a side view of a street-sweeping machine embodying our invention. 25 Fig. 2 represents a top or plan view of the machine shown in Fig. 1. Fig. 3 represents a sectional view on line *x* *x*, Fig. 1. Fig. 4 represents a sectional view on line *y* *y*, Fig. 3. Fig. 5 represents a sectional view on line *z* *z*, 30 Fig. 4, on an enlarged scale, the buckets being advanced in position. Fig. 6 represents a sectional view on line *v* *v*, Fig. 2.

Similar letters of reference indicate corresponding parts in the several figures.

35 Referring to the drawings, *A* designates a street-sweeping machine having the frame *B* and the rear running-wheels *C* with the axle *D*. Secured to the frame *B* and on the sides thereof is a conveyer *E*, which at its lower 40 horizontal portion *F* below the frame is open on the one side thereof, forming a trough, so as to admit the dirt thrown therein from the rotary brush *G*. The said conveyer *E* extends upwardly on both sides of the frame *B* and across the same, having an outlet in a 45 chute *H* on the upper portion of one side thereof. In the corners or attachments of the walls of the said conveyer *E* are suitably journaled the shafts *J*, each having sprocket-wheels *K* thereon, and on the sprocket-wheels 50 are secured the chains *L*, provided with the

V-shaped buckets *M*, which are secured thereto, as shown in Fig. 3, so that in the horizontal portions of the conveyer the dirt is pushed or drawn along the same and in the vertical 55 passage *N* it is lifted.

To prevent any return of the dirt down the side portion *P* of the conveyer, the upper horizontal portion *Q* thereof extends beyond the top of the said side portion *P* and into the 60 chute *H*. To adjust the tension of the chains *L* taking up the slack of the same, a shaft *R* with sprocket-wheels *S* and journaled in a plate *T* is provided. The said conveyer has the recesses *U* therein, so that the plates are 65 vertically guided by the pins *V*, which are secured to the said plate and pass into the said recesses. An arm or attachment *W* of the wall of the conveyer *E* furnishes a bearing for a screw *X*, the end of which works 70 against the under face of a plate *T*, so as to raise the same, and thereby press the sprocket-wheel *S* against the chain *L*, tightening the same.

The rotary brush *G*, which is mounted on a 75 shaft *Y*, extends across the under side of the frame, and on the side opposite the chute *H* has its end substantially in the plane of the outer side of the rear running-wheel on that side, so as to permit the close approach of the 80 brush to the side of the curb, and thus insure the perfect sweeping of the street.

The ends of the shafts *Y* have bearings in the slides *Z* of the boxes *A'*, which latter are secured to the under side of the frame *B*, and 85 are provided with bevel gear-wheels *B'*, which mesh with bevel-gears *C'*, firmly secured on the lower ends of the vertically-movable shafts *D'*, so as to both rise and rotate therewith, the latter having bearings in cross-pieces or 90 attachments *E'* of the boxes *A'*. Keyed on the upper ends of the said shafts *D'* are the bevel-wheels *F'*, which are supported on the upper cross-pieces *E'* and mesh with the bevel-wheels *G'* on the shaft *H'*, the latter being 95 journaled in the frame *B*. Between the axle *D* and the shaft *H'* is a shaft *J'*, which is journaled in the frame *B* and has thereon a large and a small sprocket-wheel *K' L'*, respectively, which are connected by the sprocket-chains 100 *M' N'* with the sprocket-wheels *P' Q'* on the axle *D* and the shaft *H'*, so as to communicate

rotary motion from said axle when revolving to the shaft H' and thus to the brush G.

The slides Z are vertically movable in the boxes A' by means of the links R', pivoted thereto, the elbow-levers S', pivoted to the links and to the boxes A', the rod T', connected with a rod U', connecting the upper end of the said levers, and the lever V', pivoted at its lower end to the frame B and having the rod T' connected therewith, the upper end of said lever V' extending above the frame and being adjacent to the seat W' on the frame B. A rack Z' serves to hold the lever V' in place when the brush is raised.

15 Extending across the device and in front of the brush is a curved plate A², forming a shield or guard and also a dirt-gatherer. The said plate has the studs B² at its ends, which form journals resting in the oblique slots C² in the walls of the boxes A', so as to rise and fall therein in case of inequality of the ground. Pins D² on the slides Z keep the upper end of the shield or guard A² from contact with the brush and serve to raise the said shield 20 when the brush is raised, so that it is always the same distance from the brush.

25 To rotate the sprocket-wheels K of the conveyer E, and thereby the chains L, on one of the shafts J is mounted a bevel-wheel E², which meshes with a bevel-gear F² on a shaft G², carrying a sprocket-wheel H², the latter being connected by a sprocket-chain J² with a sprocket-wheel K² on the axle D, so that rotary motion is communicated from said axle 30 to said sprocket-wheels K.

35 The sprocket-wheels I² and K² are each connected with a loose member L² of a clutch mechanism, so as to be idle on the axle D when not connected with the fast members M² thereof, and the elbow or crank lever N², which operates the fast member of the clutch of the wheel P', is connected by a rod P² with the rod U', so as to be operated by the movements of the lever V', and the fast member 40 M² of the wheel K² has an operating elbow-lever with rod Q², connected with a lever R², which is pivoted to the frame and has its handle adjacent to the seat W'.

45 Instead of removing the dirt from the conveyer E by means of the chute H, it may be conveniently removed from the rear end of the device, and for this purpose the following described mechanism is employed: A box S², having an opening T² in its top and provided with an inclined bottom U² and a discharge-valve V², is mounted on a track W², which is supported on the standards X², firmly secured to the frame B. The said box is adapted to be moved beneath the upper horizontal portion of the conveyer, so as to receive the dirt from the same through the opening Y² in the under side thereof, the said opening being closed when the discharge is from the chute H by means of a sliding plate Z².

50 The operation of the device is as follows, the parts being as shown in Fig. 1: When the

55 machine is moved forward, the brush G rotates in the direction of the arrow 1, and the dirt in contact with the brush is swept on the shield A² and brushed into the trough portion F of the conveyer, through which latter it is passed, being pushed in the horizontal portions thereof and lifted in the vertical portion N by the buckets M until it is discharged 60 either at the opening Y² into the box S² or from the chute H. In case of inequalities of the surface of the ground which is being passed over, the shield A', owing to its journals resting loosely in the slots C², is permitted to rise and fall, so that there will be no breaking or injury to these parts. If it be desired to stop the operation of sweeping, the brush can be readily raised by operating the lever V', so as to raise the slide Z, thereby 65 lifting the shaft Y with the brush, it being seen that the bevel-wheel C' is raised so as to lift the shaft D', which latter slides in the bevel-wheel F', so that the said wheel F' is not disengaged from the bevel-wheel G'. The 70 same movement of the lever uncouples the members of the clutch mechanism of the sprocket-wheel P', so that the rotation of the axle D no longer revolves the shafts J', H', D', and Y with the brush G. At the same 75 time the lever R² is operated so as to free the fast member from the loose member of the clutch mechanism of the sprocket-wheel K², thereby stopping the rotation of the shafts G² and J and the sprocket-chains L with their 80 buckets M. The machine can now be moved either forward or backward without operating the sweeping mechanism thereon. When it is desired to employ or bring in operation the said sweeping mechanism, the levers V' and R² are moved so as to lower the brush and connect the loose and fast members of the clutches of the wheels I² and K², when the machine being moved forward the brush 85 will rotate and the endless chain of the conveyer will carry the buckets, as before described.

90 Having thus described our invention, what we claim as new, and desire to secure by Letters Patent, is—

1. A street-sweeping machine having a conveyer with a receiving-trough below the frame thereof, upright passage-ways communicating with said trough, a horizontal passage-way extending across the frame of the machine, an endless belt with buckets thereon, and a rotary brush substantially parallel with said trough, said parts being combined substantially as described.

2. A street-sweeping machine provided with a conveyer having a receiving-trough with an opening in its side, a rotary brush, a shield for said brush, vertical passage-ways on the sides of the frame, a horizontal passage-way extending across said frame, and an endless belt with buckets thereon, said parts being combined substantially as described.

3. The combination of a frame, a rotary brush, a dirt-gatherer adapted to be raised and

lowered, and a conveyer with trough adapted to receive dirt from the brush and gatherer, substantially as described.

4. A street-sweeping machine having a conveyer with a receiving-trough below the frame thereof, a vertical passage therefrom, a horizontal passage-way above the frame having an opening in its under side, and a box movable on a track secured to the device having 10 an opening in its top adapted to register with the opening in the under side of the said passage-way, said parts being combined substantially as described.

5. In a street-sweeping machine, a frame 15 with boxes on its underside, slides vertically movable in the ends of said boxes, a rotary shaft journaled in said slides, a brush on said shaft, pivoted links connected with said slide, elbow-levers pivoted to the boxes, and sliding 20 rods with operating-levers, said parts being combined substantially as described.

6. In a street-sweeping machine, a conveyer having an upper horizontal passage extending at one end thereof beyond the side of a 25 descending vertical passage thereof, and an endless belt with buckets working in said passages, substantially as and for the purpose set forth.

7. In a street-sweeping machine, a frame 30 with boxes on the under side, slides in said boxes, a brush with journals having bearings in said slides, and a pivoted circular shield partially encircling said brush and adapted to be raised and lowered by the movement of

said slides, said parts being combined substantially as described. 35

8. In a street-sweeping machine, a frame with boxes having slides therein, a rotary brush mounted on said slides, a shield adapted to receive the dirt swept by the brush, and 40 a conveyer having a trough adapted to receive the dirt from the brush and shield, said parts being combined substantially as described.

9. In a street-sweeping machine, a frame 45 with boxes having the slots C² therein, a rotary brush journaled in slides in said boxes, and a shield journaled in said slots and partially encircling said brush, said parts being combined substantially as described. 50

10. In a street-sweeping machine, a pivoted shield for the rotary brush thereof, having its journal-bearings freely mounted in slots, substantially as and for the purpose set forth.

11. In a street-sweeping machine, a rotary 55 brush having its journal-bearings in vertically-movable slides, a pivoted shield partially encircling said brush, studs on the slides supporting the upper end of said shield, and mechanism, substantially as described, for 60 raising and lowering said brush, said parts being combined substantially as described.
